Alfred Newton of Morden Connecticut
Letters Patent

This Schedule referred to in these Letters Patent and making part of the same containing a description of the said Alfred Newton himself of his improvement in the spiral Screw Auger.

To all to whom these presents shall come. Know Ye that I, Alfred Newton of Morden in the County of New Haven, State of Connecticut, have invented a new and useful improvement in the Spiral Screw Auger, and that the following is a full and exact description of the construction and operation of the said instrument as invented or improved by me.

That portion of the metal used to form the Screw, Lips, and tips of the improved Auger is, first forged into a triangular shape in the usual way, then each side of the triangular bed is depressed or hollowed out by means of a swedge, or in any other convenient way, so that the hollow or depression in the deepest part for an inch and a half be about three eighths of an inch on each side of the triangle. If the Auger is to be made of a large size, the hollow should be sunk a little lower, if of a smaller size a little less than the above mentioned proportion. This swedging or hollowing should not extend quite to the end ~~and~~ whether the Lips and screw are to be formed, but should leave a small accumulation of metal there to be wrought into the Lips and screw. The metal being thus prepared with three concave sides and three edges, is twisted into a spiral form in the usual way. On each of the three edges or concave, and at the end thereof out of the metal left there for that purpose, is formed a cutting lip or edge, in the usual manner heretofore practiced, and in the centre is formed the screw of the Auger with three threads, one for each edge or side of the twist and differing from the common screw in shape and mode of formation, only in its having three threads as aforesaid. If the shank and spiral part are made of iron, the screw and lips would need to be made of steel added at the end for that purpose.

Some of the advantages of the instrument thus improved, are additional strength, from the fact that there is an accumulation of metal in the centre of the auger, greater ease in boring from the fact that there are three cutting lips instead of one or two as in other augers, and more steadiness of operation from the fact that the lips are so placed that only one cuts directly across the grain of the wood at the same instant, and each one of the lips operates differently as to the manner of taking the grain at the same moment.

Figure 1, in the annexed drawing exhibits a view of the screw, two of the lips, and of the spiral twist and part of the shank. Fig. II. Represents an end view of the improved auger, the spiral is seen in the centre, and the lips, or cutters at a b c. Fig. 3. shows a section of the auger made perpendicularly to the centre and helps to understand the shape which the metal had before it was twisted at d e f showing the edge with the hollow, or concavities between them.

I claim of my improvement, for which I solicit a Patent, the formation of an auger with three lips, or cutters, and a triple spiral in contradistinction to the auger now made, which so far as I know has hitherto been made with not more than two lips, or cutters, and a double spiral formed by twisting a flattened piece of metal. I do not claim the whole instrument, as my invention, nor the triple thread in the screw of the auger, nor that I am the inventor of a screw auger over spiral twist auger which ever singly or doubly twisted, but I claim only what I have above stated as an improvement upon each spiral twist and screw auger, as are now in use, by the addition and formation of a third cutter, and spiral, securing the advantages above specified, and described. In testimony that the above end forgoing is a true Specification of my said improvement, I hereunto set my hand at New Haven this 30th day of July 1834.
